UNITED STATES PATENT OFFICE

133,291

DESIGN FOR A VENTILATING UNIT

Milton A. Powers, Detroit, Mich.

Application March 29, 1941, Serial No. 99,993

Term of patent 3½ years

To all whom it may concern:

Be it known that I, Milton A. Powers, a citizen of the United States, residing at 325 Fiske Avenue, Detroit, in the county of Wayne, and State of Michigan, have invented a new, original, and ornamental Design for a Ventilating Unit, of which the following is a specification, reference being had to the accompanying drawing, forming part thereof.

Figure 1 is a perspective view of a ventilating unit showing my new design;

Figure 2 is a top plan view thereof; and
Figure 3 is an end elevational view of Figure 2.

I claim:

The ornamental design for a ventilating unit, substantially as shown.

MILTON A. POWERS.
